GUARD UNIT FOR A TRICYCLE OR SIMILAR ARTICLE

Donald W. Gill, Amberly Village, Ohio, assignor to The Frank F. Taylor Company, Cincinnati, Ohio, a corporation of Ohio

Application April 10, 1957, Serial No. 45,659

Term of patent 14 years

(Cl. D34—15)

Figure 1 is a side perspective view of a guard unit for a tricycle or similar article showing my new design, the opposite side having substantially the same appearance.

The dotted line showing is for illustrative purposes only.
I claim:

The ornamental design for a guard unit for a tricycle or similar article, substantially as shown and described.
